CLAIM

The ornamental design for a barbecue grill grease collection apparatus, as shown and described.

DESCRIPTION

FIG. 1 is a perspective view of a barbecue grill grease collection apparatus showing my new design;

FIG. 2 is a top plan view thereof;

FIG. 3 is a bottom plan view thereof;

FIG. 4 is a front elevational view thereof, the opposite side being a mirror image thereof; and,

FIG. 5 is a left side elevational view thereof; the opposite side being a mirror image thereof.
